CLAIM

The ornamental design for a revolving stand-alone wire display shelving unit, as shown.

DESCRIPTION

FIG. 1 is a perspective view of the revolving stand-alone wire display shelving unit;

FIG. 2 is a front view of the revolving stand-alone wire display shelving unit;

FIG. 3 is a rear view of the revolving stand-alone wire display shelving unit;

FIG. 4 is a left side view of the revolving stand-alone wire display shelving unit;

FIG. 5 is a right side view of the revolving stand-alone wire display shelving unit;

FIG. 6 is a top plan view of the revolving stand-alone wire display shelving unit; and,

FIG. 7 is a bottom plan view of the revolving stand-alone wire display shelving unit.
